UNITED STATES PATENT OFFICE

HOLLIS B. CRUM, OF SOUTH MILWAUKEE, WISCONSIN

BRICK-SETTING MACHINE

Application filed March 31, 1928. Serial No. 266,411.

My present invention relates to brick setting machines, and more particularly to an improved hydraulic brick setting machine.

In the brick setting machines heretofore employed, it has been usual and customary to have a brick gripping device for engaging the finger courses of a unit stack of brick and operable by inflexible mechanism, such as pivoted links and bars, or by flexible or yielding mechanism, such as gripping fingers controlled by resilient means, such as springs. In either class of devices, each individual brick gripping element is and must be separately adjustable and because of the inability to adjust the mechanism so that the same amount of pressure is applied equally to each of the brick gripping devices and because of the fact that the brick vary in thickness, such devices have not come into the general use to which they are seemingly entitled. With regard to brick gripping devices of the pivoted lever or bar type, the adjustment of the elements thereof is positive, and once having been set, the same amount of movement is given to the parts and, therefore, the same pressure is exerted by such parts, regardless of the thickness of the brick with which such elements are in engagement. Consequently it might, and frequently did happen, that such gripping devices failed to hold the brick at all and in other cases the brick was subjected to such severe pressure as to destroy the same. Where it was attempted to substitute spring means to compensate for the variations in thickness of the bricks being worked upon, the question of adjustment is the all-important factor, particularly as each spring has its individual characteristics as regards loads submitted thereto at different stages of compression of the springs and this type of lifting device, though much better than the positive link and bar type, yet has not come into general use.

In devising the subject matter of the present invention, I am enabled to obviate the defects of prior devices and to obviate the difficulties attendant thereon as above pointed out, and have devised a lifting or setting mechanism in which a plurality of individual brick gripping devices are simultaneously

operated from a single source and each individual gripping device is arranged to produce the same identical pressure on a brick being gripped.

In carrying out my invention, I provide a plurality of parallelly arranged fingers, as is usual in this type of apparatus, and associated with each finger is a plurality of brick gripping devices, such devices being associated with a source of fluid pressure that is common to every finger and to every gripping device carried thereby. The form of fluid pressure is preferably hydraulic and with this type of power, I am enabled to transmit to each individual brick gripping device a predetermined pressure and the pressure is generated by the weight of the setting device itself and its associated load of brick.

The principal object of my invention, therefore, is an improved setting machine.

Another object of my invention is an improved hydraulic setting machine.

A further object of my invention is an improved setting machine having means for simultaneously operating a plurality of gripping devices and subjecting the same to a uniform pressure.

Other objects and novel features of the construction and arrangement of parts comprising the device, will appear as the description of the invention progresses.

In the accompanying drawings illustrating preferred embodiments of my invention,

Fig. 1 is a rear end elevation;

Fig. 2 is a partial plan view of Fig. 1;

Fig. 3 is a side elevation;

Fig. 4 is a section on the line 4—4 of Fig. 1;

Fig. 5 is a partial front elevation;

Fig. 6 is a section on the line 6—6 of Fig. 4;

Fig. 7 is a section on the line 7—7 of Fig. 4;

Fig. 8 is an elevation of a clamping unit disassociated from its surrounding mechanism;

Fig. 9 is a section on the line 9—9 of Fig. 1;

Fig. 10 is a section on the line 10—10 of Fig. 1;

Fig. 11 is a section on the line 11—11 of Fig. 1;

Fig. 12 is a section on the line 12—12 of

Fig. 4 showing the gripping elements in one position, and

Fig. 13 is a view similar to Fig. 12 but showing the gripping elements in open or operative position.

Referring to the drawings, 10 designates a flat plate or bar of suitable width and length, which has formed integral therewith and on the under side thereof an elongated chamber 11. Secured to the under face of the material forming the walls of the chamber 11 by bolts 12, are bearing members 13. In the lower ends of each of the bearing members 13 is mounted a shaft 14, these shafts being in alignment with each other, as clearly shown in Fig. 1, and the outer ends of each of said shafts are threaded to receive nuts 15. Rotatably mounted on each of the shafts 15 and at each side of the bearing members 13 is a forwardly extending lifting finger 16. Also secured to the under face of the material forming walls of the chamber 11 by bolts 17 is a bearing member 18, such bearing member being provided with a shaft 19 held in position by a nut 20, and on such shaft is rotatably mounted a forwardly extending lifting finger 21. From an inspection of the drawings, and particularly Fig. 1, it will be apparent that the lifting fingers 16 are arranged in pairs, with the exception of the lifting finger 21 associated with the bearing member 18. Intermediate the ends of each pair of lifting fingers 16, as above described, is a spacing block 22, which, by reference to Fig. 7, will be seen to be recessed in the inner or opposing faces of the pairs of lifting fingers 16 and such fingers are held in close association with the blocks 22 by means of threaded bolts 23. Each pair of lifting fingers, therefore, with the exception of the lifting finger 21, as above described, move in unison. Formed integral with the rectangular plate 10, and extending downwardly from the front edge thereof, is a plate 24, the lower end of which is recessed, as indicated at 25 in Fig. 4. Fitting in the recess 25 so as to have the front face thereof flush with the front face of the plate 24, are downwardly depending members 26, such members being held in position by bolt 27, there being one of such members for each connected pair of lifting fingers 16. The lower end of each of the members 16 have formed integral therewith rearwardly extending members 28 and on which the lower end of the spacing blocks 22 rest when the outer ends of the lifting fingers 16 are in their lowermost position. Also secured to the under face of the material forming walls of the chamber 10, adjacent to the end of the plate 24, is secured a downwardly extending plate 29 which is provided with a rearwardly extending ledge 30 that is engaged by a bar or block 31 secured to the inner face of the lifting finger 21 in the same relative position thereon as is occupied by the block 22 associ-

ated with the pairs of lifting fingers 16. While the downward movement of the outer free ends of the lifting fingers 16 and 21 is limited by the ledges 28 and 30, the upper movement thereof is limited by the lower edge 70 of the plate 24, as clearly shown in Fig. 4. While the outer free ends of the lifting fingers 16 and 21 are in their lowermost position, the upper edges of all such lifting fingers lie in a horizontal plane that is at right angles 75 to a vertical plane in which lies the front face of the plate 24 and elements 26. Secured to the upper face of the plate 10 by bolts 32 and symmetrically arranged on either side of the center of the length of such plate 10 are standards 33. Forming part of such standards 33 and arranged parallel to but spaced apart from each other are vertically arranged uprights 34 and in each of such uprights are arranged guideways 35 and 36, the guideways 35 being of equal length and arranged opposite each other, as are also the guideways 36. 37 designates a U-shaped member at the extremity of the arms of which are arranged outwardly extending stub shafts 38, and on each such shaft is an anti-friction roller 39, which rides in the guideway 35 above described as being formed in the members 34. At the end of the arms of the U-shaped members 37, remote from the stub shafts 38, are arranged stub shafts 40, such stub shafts extending laterally outward therefrom and being provided on their outer ends with anti-friction rollers 41 that engage in the guideways 36. The U-shaped member 37, therefore, is capable of vertical movement within the limits of the length of the guideways 35 and 36. Secured to the U-shaped member 37 on opposite sides thereof and adjacent to the stub shafts 40, by bolts 42, are outwardly extending parallelly arranged lifting bails 43, such bails each being provided with a hole 44 at the extremity thereof. The bails 43 are two in number and both equal in length, so that the holes 44 therin are in alignment with each other. On the side of the U-shaped member 37 opposite the bails 43, secured by bolts 45, are short bails 46, each provided with holes 47, and the bails 46 form practically a rearward continuation of the bails 43 and the holes 47 in the bails 46 being in alignment with each other, the holes 44 and 47 form a four-point suspension means for suspending the U-shaped member from any device, such as a lifting crane. Formed in the members 46 are bearings 48 and in these bearings there is rotatably mounted a shaft 49, provided intermediate its ends with an operating lever 50. Secured to the shaft 49 and at each end thereof is a dog 51, these dogs being adapted to engage with a latch 52, formed integral with and extending upwardly from the members 34. With the parts in the position shown in Figs. 1, 3 and 4, for example, it will be obvious that with the dogs 51 engag- 130

ing with the latches 52, that the anti-friction rolls 41 and 39 will be at the lowermost ends of the guideways 36 and 35 respectively and, therefore, the U-shaped frame member 37 will be retained in its lowermost position with regard to the members 34 and the parts mounted on and carried thereby. In this position, the entire mechanism may be transported by suitable means to any place desired and 10 when thus held, the various operating parts will be in their normal or inoperative position.

Each of the lifting fingers 16 is provided near its top edge with a longitudinal passage 15 53, such passage extending substantially throughout the length of the finger, but being closed at the outer end thereof. At intervals along the length of the lifting fingers 16 and on the under face or edge thereof are transverse journals or grooves 54 and extending 20 from the bottom face of each of the journals or grooves 54 upwardly, so as to connect with the longitudinal passage 53, is a passage 55. Also extending from the bottom face of 25 the transverse passages 54, parallel to the passage 55 and located one on each side of such passage, are holes or depressions 56, such holes or depressions, however, not extending into the longitudinal passage 53. 30 On the bottom face or edge of each of the fingers 16, adjacent each edge of the transverse passages 54, are drilled and tapped holes 57.

Referring now to Fig. 8, wherein is shown 35 an elevation of a clamping unit adapted to be positioned in a transverse passage 54 and a passage 55, 58 designates a block that fits into the transverse passage 54 and with the lower end thereof extending laterally outward on 40 each side to form shoulders 59 that engage with the lower edge of the fingers 16, such shoulders 59 being drilled and counterbored, as indicated at 60, in alignment with the drilled and tapped hole 57 in the fingers 16, 45 and in which drilled and counterbored holes 60 and tapped holes 57 screw bolts 61 and by means of which the block 59 and attached parts are firmly held in position on the under face or edge of the lifting fingers 16. There 50 are a plurality of such blocks 58 for each of the fingers 16, as will be clearly evident from an inspection of Fig. 4, and each block 58 is provided with a transverse opening 62, which acts as a housing for elements to be described. 55 Each of the blocks 58 is provided with a pair of shafts 63 arranged in alignment with each other and held in position in the block 58 by pins 64. The inner ends of each of the shafts 63 extend into the opening 62 but are separated from each other and on such inner ends are pivotally mounted one end of links 65, such links being held against longitudinal displacement on such shaft 63 by pins 66. The other ends of the links 65 are pivotally mounted 60 to a single shaft 67, such shaft being associated with the links 65 by pins 68. On the shaft 67 between the links 65 is pivotally mounted a gripping lever 69, the free end of which is capable of moving laterally outward with respect to the lifting fingers 16, and the 70 other end is rotatably mounted on a shaft 70 arranged parallel to the shaft 67. The attaching end of the lever 69 with the shaft 70 is forked, as indicated at 71, and in such forked portion and on the shaft 70 is pivotally attached the lower end of a piston 72. The upper end of this piston is machined to be a close sliding fit in the passage 55, that is connected to the longitudinal passage 53. It is obvious, therefore, that if the piston 72 80 occupies the relation with respect to the passage 55, as indicated in Fig. 13, that the lever 69 will be moved upwardly and will be housed within the limits of the block 58, which block 85 obviously is of the same width as the width of the fingers 16 and that when such piston 72 is moved downward with respect to the passage 55, that the lever 69 will be so operated as to throw its lower free end outward laterally with respect to the fingers 16, as 90 clearly shown in Fig. 12. At the upper end of the piston 72 is attached, by means of screw 73, a piston washer 74 which insures a tight joint to any pressure that may be in the passage 53 urging the piston 72 downward in the passage 55. Pivotally attached to the shaft 70 at each end thereof and prevented from being removed from said shaft by pins 75 is an upwardly extending pin 76. These pins 76 have secured at their upper 100 ends, by pins 77, a washer 78 and between the under face of each of the washers 78 and the upper face of the block or abutment 58, is a coil spring 79 and the coil spring 79, together with the rod 76, fit loosely into the 105 holes or depressions 56 arranged one on each side of the passage 55. It is obvious from an inspection of Fig. 8 that if the piston 72 is moved downwardly to cause the free end of the lever 69 to move from the position 110 shown in Fig. 13, to that shown in Fig. 12, that the spring 79 will be compressed and that if the piston 72 is freed, that the tension of the springs 79 will tend to draw the piston 72 back into their normal position, as shown 115 in Fig. 13.

Attached to the upper central portion of the member 10, by bolts 80, is a member 81 provided with a central chamber 82 for a purpose to be hereinafter described, and such central chamber 82 is connected by means of passage 83 with the elongated chamber 11. The material forming the rear wall of the elongated chamber 11 is drilled at intervals to receive one end of a connecting member 84, there being one such member 84 for each of the lifting fingers 16. The member 84 is secured in position with respect to the elongated chamber 11 by bolt 85. On each of the lifting fingers 16, on the 120 125 130

upper edge thereof adjacent to the pivot end, is an upwardly extending projection 86 drilled and tapped in alignment with the longitudinal passage 83 to receive a bolt 87. 5 Lying between the projection 86 and the rearward end of the longitudinal passage 83 is a connecting member 88, which is securely clamped in position by the bolt 87. The member 88 is provided with a passage 89 that 10 connects with the longitudinal passage 83 and extending between the member 88 and the member 84 is a flexible tube 90, such tube, therefore, forming the connecting link between the longitudinal passage 83 and the 15 elongated chamber 11 and allows fluid to flow from the chamber 11 to the longitudinal passages 83 and vice versa.

The member 81 on either end thereof is machined to receive as a sliding fit a piston 91 and these pistons are slideable toward each other into the chamber 82, for a purpose to be hereinafter described. The outer face of each end of the member 81 is drilled and adapted to receive bolts 92 that act to hold 25 stuffing boxes 93 in position on the member 81 and surrounding the pistons 91 and between the stuffing boxes 93 and the machined ends of the member 81 is packing 94 arranged for the purpose of maintaining a tight joint 30 between the machined ends of the member 81 and the pistons 91. To the outer end of each of the pistons 91 is secured, by pin 95, one end of a connecting rod 96. These connecting rods extend outward in a horizontal 35 direction and pass through guides 97 on the member 34. The outer ends of the connecting rods 96 are pivotally attached to one end of links 98, the other end of such links being 40 pivotally connected to the lower end of one of the arms 99 of a bell crank lever that is pivotally mounted on a shaft 100 adjacent to the upper end of the member 33. The free end of the other arm 101 of each of the bell crank levers is pivotally attached 45 to the lower end of links 102 and the upper end of such links 102 are pivotally attached to the U-shaped frame member 37 adjacent to the central point or portion thereof.

From an inspection of Fig. 1, it will be 50 obvious that an upward movement of the U-shaped frame member 37 causes an upward movement of the free ends of the arms 101 of the bell crank lever pivoted at the points 100 and, therefore, an inward movement of the free ends of the arms 99 of such bell crank lever, causing thereby an inward movement of the pistons 91 toward each other and into the chamber 82, thus compressing 55 any fluid such as water that may be in such chamber and transmitting a pressure therefrom to cause an outward or downward movement of the pistons 72 in the passages 55, thus causing an outward movement of the free ends of the levers 69, thus moving the 60 same from the position shown in Fig. 13 to

that shown in Fig. 12. If at this time a pair of rows of brick 105 are between adjacent fingers 16, it will be obvious that such brick will be held gripped between the levers 69 and the adjacent face of the fingers 16. 70 Formed integral with the member 81 and extending upwardly therefrom is a cylindrical member 106, this member being enlarged at its top and open, and the open end closed by a cover plate 107 secured to the member 106 by bolts 108. The interior of the member 106 at its lower end is chambered, as indicated at 109, to receive as a sliding fit an open ended piston 110 provided with a spring ball valve 111 at its lower end and the chamber 109 communicates with the chamber 82 by means of a port 112. Within the member 106 and adjacent to the top of the chamber 109 is provided a stuffing box 113 held in position by bolts 114 and surrounding the open ended pistons 110. Between the stuffing box 113 and the body of the member 106 is compressible packing 115, this being for the purpose of maintaining a tight joint 80 between the slideable piston 110 and the chamber 109. The cover 107 is provided with a centrally located hub 116 threaded to receive a screw plug 117, such screw plug being provided with a perforation 118 communicating with the interior of the hollow piston 110 and being closed by a screw plug 119. On the inner end of the plug 117 is located a washer 120 provided with a perforation 121 in alignment with the perforation 118 and lying between the lower face of the washer 120 and the closed end of the piston 110 is a coil 90 spring 122.

If the apparatus above described is suspended from any suitable lifting device, such as a crane, by a four-point suspension attached at the holes 44 and 47 in the members 43 and 46 respectively, and if, under these circumstances, the parts of the apparatus are in the position indicated in Figs. 1 and 4, for example, it is obvious that an upward movement of the members 43 and 46 will cause an upward movement of all of the apparatus mounted on or associated with the elements 33 and 34, due to the fact that the dogs 51 carried on the U-shaped member 37, and therefore, directly attached to the members 43 and 46, engage with latches 52 formed integral with and at the upper end of the members 34, and that under these circumstances, the gripping levers 69 associated with the lifting fingers 16 will be in the position shown in Fig. 13—that is, under these circumstances, it is possible to move the plurality of parallelly arranged lifting fingers 16 into the spaces between the finger courses 125 at the bottom of a unit stack of brick 105. If, therefore, after the plurality of parallelly arranged fingers 16 have been arranged under the unit stack of brick composed of the brick 105 and between adjacent finger courses 130

thereof, the operator by pulling on the lever 50 rotates the shaft 49 sufficiently to withdraw the dogs 51 from engagement with the latches 52 and a lifting action is given to the members 43 and 46 and, therefore, to the U-shaped frame member 37, it is obvious that the lifting movement of the U-shaped member 59—which is guided in a vertical direction by means of the anti-friction rolls 41 and 39, moving in the vertical guideways 36 and 35 respectively, that the inner free ends of the arms 101 of the bell crank levers pivoted at the points 50 will likewise be moved upwardly, thereupon forcing, through their connection with the arms 99 and rod 96, the pistons 91 toward each other into the chamber 82. If, under these circumstances, we consider the chamber 82, as well as the elongated chamber 11, to be filled with a liquid, such as water or oil, and also the hollow pistons 110 as well as the interior of the member 106, to be filled with the liquid, then the inward movement of the pistons 91 will generate a pressure in such liquid and the pressure will be communicated through the liquid to cause a movement outward or downward of the pistons 72 in the passages 55, with the result that the gripping levers 69 will be rotated about their axis and brought from the position shown in Fig. 13 to that shown in Fig. 12, thereby gripping the lower courses of brick 105 between one face of the fingers 16 and the gripping levers 69. The combined displacement of the two pistons 91 is approximately double the amount required to operate the entire set of gripping levers 69, and when a pressure of approximately one hundred and fifty pounds per square inch has been reached, a sufficient amount of the fluid has passed through the channel 83 to operate the gripping mechanisms and do the necessary work. Any excessive pressure over that necessary to do the work will cause a flow of liquid through the passageway 112 and will cause an upward movement of the open ended piston 110 and will cause a compression of the spring 122, the forward movement of the open ended piston 110 being sufficient to accommodate the surplus from the displacement of the pistons 91. Should there be any leaks in the system, a certain amount of fluid will necessarily be lost, and the spring 122, therefore, with its associated open ended piston 110 acts as an accumulator to maintain the necessary pressure on the gripping levers 69. In order that a sufficient amount of oil may be kept for use in the system, the upper end of the member 106 is provided with an oil indicator 126, and should the oil drop below a certain predetermined amount, the operator may, by removal of the plug 119, insert through the perforation 118, a sufficient amount to bring the supply back to normal. The load of brick comprising the unit made up of the individual bricks

105, together with that part of the machine movable relatively to the U-shaped member 37 and attached parts, is calculated to weigh approximately six thousand pounds and is sufficient to generate a pressure of approximately four hundred and fifty pounds per square inch, but the normal working pressure is approximately one hundred and fifty pounds per square inch and the difference is absorbed by the piston 110.

After the unit stack of brick has been brought to the position desired, the U-shaped member 37 lowered to its lowermost position, or until the dogs 51 engage with the latches 52, and the weight of the moving members is sufficient to cause a retraction of the pistons 91, which are thus brought back exactly to their original position. If, during the operation of the device, any fluid has leaked out of the system during the period it was under pressure, a partial vacuum will be created in the chamber 82 and this partial vacuum will be sufficient to overcome the tension of the spring in the ball spring valve 111 and enough fluid will pass through said valve 90 from the reservoir above into the chamber 82 to make up the deficiency and bring the system back to normal again.

While I have necessarily shown and described the preferred embodiment of my invention somewhat in detail, it is to be understood that I may vary the size, shape and arrangement of parts within wide limits without departing from the spirit of the invention.

Having thus described my invention, what I claim as new is:

1. In a brick setting machine, the combination of a plurality of lifting fingers, a brick gripping device mounted on each of said fingers, each gripping device operable to engage with one face of the brick and grip the same and force the brick into engagement with the adjacent finger, hydraulic means for operating said gripping devices simultaneously and means for operating the hydraulic means to apply pressure to the gripping devices proportional to the weight of bricks on the fingers.

2. In a brick setting machine, the combination of a plurality of parallelly arranged lifting fingers adapted to be positioned under a stack of brick and between the finger courses of such stack, a plurality of independently operable brick gripping devices mounted on each of said fingers, the plurality of gripping devices on each finger co-operating with the adjacent finger to grip the finger courses therebetween, hydraulic operating means for operating said gripping devices simultaneously and means for operating the hydraulic means to apply pressure to the gripping devices proportional to the weight of bricks on the fingers.

3. In a brick setting machine, the combination of a framework, a plurality of parallelly arranged brick lifting fingers mounted thereon, a plurality of brick gripping devices 5 mounted on each of said fingers and each gripping device co-operating with its adjacent finger to grip and lift the finger courses of a unit stack of brick, a lifting mechanism 10 slidably mounted in said framework, an hydraulic operating means for operating the brick gripping devices, and connections between the lifting frame and the first said frame for controlling the hydraulic means.

4. In a brick setting machine, the combination 15 of a framework, a plurality of pivotally mounted brick lifting fingers parallelly arranged with respect to each other, means permitting limited pivotal movement of said fingers individually of each other and with 20 respect to the framework, a plurality of brick gripping devices mounted on each of said fingers, an hydraulic operating means for said gripping devices mounted on said framework, a lifting frame slidably mounted with 25 respect to said frame, and connections for operating the hydraulic device extending between the said frames whereby the pressure generated by the hydraulic operating means is dependent on the load carried on the lifting 30 fingers.

5. In a brick setting machine, the combination 35 of a framework, a plurality of pivotally mounted brick lifting fingers parallelly arranged with respect to each other, means permitting limited pivotal movement of said fingers individually of each other and with 40 respect to the framework, a plurality of brick gripping devices mounted on each of said fingers, an hydraulic operating means for said gripping devices mounted on said framework, a lifting frame slidably mounted with 45 respect to said frame, connections for operating the hydraulic device extending between the said frames, whereby the pressure generated by the hydraulic operating means is dependent on the load carried on the lifting 50 fingers, and means associated with the hydraulic operating means for maintaining the pressure transmitted to the lifting devices substantially constant.

6. In a brick setting machine, the combination 55 of a supporting framework, a plurality of parallelly arranged brick lifting fingers pivotally mounted thereon, means on said frame permitting limited pivotal movement of said brick lifting fingers, a plurality of hydraulically operable brick lifting devices mounted on each of said lifting fingers, a lifting 60 frame slidably mounted in said supporting frame, an hydraulic mechanism mounted on the supporting framework and controlling operation of the brick gripping devices, operating connections between the lifting frame 65 and the hydraulic device for operating the

hydraulic device, the pressure generated by the hydraulic device depending on the load carried on and by the lifting fingers, means associated with the hydraulic device for maintaining the pressure transmitted therefrom to the gripping devices substantially constant, and means associated with the hydraulic device for automatically maintaining a predetermined amount of liquid in the system.

In testimony whereof, I have signed my name to this specification.
